UNITED STATES PATENT OFFICE.

WILLIAM J. LOGGIE, OF FRANKFORT, KENTUCKY, ASSIGNOR TO UNION SPECIAL MACHINE COMPANY, OF CHICAGO, ILLINOIS, A CORPORATION OF ILLINOIS.

FOLDER OR SEAM-OPENER FOR SEWING-MACHINES.

1,340,782.

Specification of Letters Patent.

Patented May 18, 1920.

Application filed November 27, 1916. Serial No. 133,708.

To all whom it may concern:

Be it known that I, WILLIAM J. LOGGIE, a citizen of the United States, residing at Frankfort, in the county of Franklin and State of Kentucky, have invented certain new and useful Improvements in Folders or Seam-Openers for Sewing-Machines, of which the following is a description, reference being had to the accompanying drawing and to the figures of reference marked thereon.

My invention relates to sewing machines and particularly to a seam opener and folder whereby a seam previously formed by superposing and stitching together the marginal portions of two plies of fabric, may be opened out and the marginal edges stitched under the body fabrics, thus making a flat seam.

The attachment has been especially designed for use in connection with stayng machines and the object is to provide an attachment having a central seam opening rib or guide coöperating with complementary guiding portions whereby the seam formed by superposing the two edges of fabric may be guided, and the marginal edges spread positively and underfolded and then fed to the two line stitch forming mechanism of such a machine.

Another object of the invention is to so arrange the parts as that the central rib or guide will positively enter between the two marginal edges and spread the edges laterally whereby in loading the device hand manipulation of the marginal edges to spread them will not be necessary.

To carry out the above objects, the invention consists in the various matters herein-after described and referred to in the appended claims.

The invention is illustrated in the accompanying drawings, in which Figure 1 illustrates a portion of a sewing machine with my improved folder and seam opening attachment applied thereto;

Fig. 2 is a front view thereof.

Fig. 3 is a central vertical sectional view on the line 3—3 of Fig. 1.

Fig. 4 is a transverse sectional view on the line 4—4 of Fig. 1, showing the fabric in position.

Fig. 5 is a view similar to Fig. 4 on the line 5—5 of Fig. 1, showing the fabric folded and ready to be stitched, and

Fig. 6 is a detail view, showing the abutted folded edges of the fabric and the binding strip sewed thereto.

In the drawing, 1 represents the bed plate of a sewing machine of well known type, 60 having stitch forming mechanism, including two needles 2, 2, arranged obliquely to each other respecting the line of feed and coöperating with two loopers 3, 3, whereby two lines of stitching are formed by the 65 coöperation of the needles and loopers.

The bed plate has the usual throat plate 4 with the needle and feed slots. The presser foot which is shown at 5 has a central keel 6. The attachment which forms the 70 subject matter of the invention consists of a base piece 7, attached to the bed plate by screws 8.

Adjustably attached to the base piece by screws 9 and elongated slots 10 are spaced 75 guiding members 11, the front portions 12 of the walls thereof being vertical and spaced apart, parallel to each other, while the rear portions are undercut as at 13, forming recesses.

Intermediate the spaced guiding members 11 is a center guide or fin 14, substantially V-shaped in cross section and with side walls 15 flaring from the apex rearwardly, the side walls forming with the undercut portions 13 of the guiding members 11, folding and guiding recesses for the marginal edges of the fabrics 16.

Two pieces of fabric 16, whose edges have been superposed and united by a line of 90 stitching 17 and which it is desired to stay or cover, are fed to the sewing machine with their marginal superposed edges passing vertically between the front portion 12 of the guiding members 11. The apex of the 95 center guide or fin 14 enters between the marginal edges 18 and opens the seam, the flaring walls 15 spreading the marginal edges apart and coöperating with the undercut portions 13 of said guiding member to 100 underfold and flatten out the marginal edges and deliver them under the presser foot 5 of the sewing machine whence they are fed to the stitch forming mechanism and sewed

to the respective body portions of the fabrics, the keel 6 of the presser foot riding in the center line of the seam.

It will be seen that by the construction herein described, the marginal edges of previously seamed fabrics may be placed between the vertical walls of the spaced guiding members, and automatically guided and spread out flat by the central fin and fed to the stitch forming mechanism of the sewing machine.

The base piece 7 has a recess 19 in its under face, which recess is centrally disposed relative to the center guide 14. This recess is adapted to receive a guide and facing strip. The facing strip will be stitched to the out-turned edge portions of the fabric sections by the needles 2—2.

Having thus described my invention, what I claim as new and desire to secure by Letters Patent, is:—

1. In a device for separating and laterally turning the seamed edges of fabric sections, the combination of a central guide provided with an apex at its front end and with flaring sides extending rearwardly from said apex, spaced guiding members located at opposite sides of the apex of said central guide, said apex of the central guide being disposed midway between the front and rear edges of said spaced guiding members, whereby said guiding members operate to

center and direct the fabric sections to the central guide, and said guiding members having side walls partially overlapping the flaring sides of said central guide.

2. An attachment for folding the marginal edges of a previously seamed fabric, comprising spaced guiding members having vertical parallel walls throughout a portion of their length and merging into flaring laterally arranged guiding recesses, and a central guide formed with flaring walls complementary to the flaring recesses in the spaced guiding members.

3. An attachment for folding the marginal edges of a previously seamed fabric, comprising spaced guiding members having vertical parallel walls throughout a portion of their length and merging into flaring laterally arranged guiding recesses, and a central guide formed with flaring walls complementary to the flaring recesses in the spaced guiding members, the forward end of the central guide terminating in the space between the vertical walls of the spaced guiding members.

In testimony whereof I affix my signature in the presence of two witnesses.

WILLIAM J. LOGGIE.
